DESIGN FOR A PARKING METER CASING

John E. Jones, Long Beach, Calif.

Application April 17, 1939, Serial No. 84,351

Term of patent 7 years

To all whom it may concern:

Be it known that I, John E. Jones, a citizen of the United States, residing at 4107 East Second Street, Long Beach, in the county of Los Angeles and State of California, have invented a new, original, and ornamental Design for a Parking Meter Casing, of which the following is a specification, reference being had to the accompanying drawing, forming a part thereof.

Figure 1 is a side elevation of a parking meter casing showing my new design, and

Figure 2 is an opposite side elevation thereof.

I claim:

The ornamental design for a parking meter casing, as shown.

JOHN E. JONES.
